UNITED STATES PATENT OFFICE

107,684

DESIGN FOR A BALLOON

Elmer E. Krueger, Chicago, Ill., assignor to Lee-Tex Rubber Products Corporation, Chicago, Ill., a corporation of Delaware

Application July 3, 1937, Serial No. 70,256

Term of patent 7 years

To all whom it may concern:

Be it known that I, Elmer E. Krueger, a citizen of the United States, residing at Chicago, in the county of Cook and State of Illinois, have invented a new, original, and ornamental Design for Balloons, of which the following is a specification, reference being had to the accompanying drawing, forming part thereof, wherein:

Figure 1 is a side elevation; and

Fig. 2 is an end elevation of a balloon showing my new design.

The instant design consists essentially of a substantially cylindrical balloon body having a rounded end from which a helical undulation extends throughout the length of the body and terminates in a spiral at the other end.

I claim:

The ornamental design for a balloon, as shown and described.

ELMER E. KRUEGER.
